UNITED STATES PATENT OFFICE.

JULIAN F. DENISON, OF NEW HAVEN, CONNECTICUT, ASSIGNOR TO GOTTFRIED PIEL, OF NEW YORK, N. Y.

GASOLENE-PUMP.

1,320,607.

Specification of Letters Patent. Patented Nov. 4, 1919.

Application filed May 12, 1917. Serial No. 168,118.

To all whom it may concern:

Be it known that I, JULIAN F. DENISON, a citizen of the United States, and resident of New Haven, in the county of New Haven and State of Connecticut, have invented certain new and useful Improvements in Gasolene-Pumps, of which the following is a specification.

My invention relates in general to a device for elevating liquids out of a receptacle and one form is utilized for forcing water to the different places in a boat. In this disclosure the invention will be illustrated specifically in its adaption to a pump construction, in a system for supplying liquid fuel to the carburetor of an internal combustion engine such as is used in automobile driving plants.

Devices of this kind now in general use usually require either an air tight condition of the liquid containing tank where the pressure feed system is used or require expensively actuated pump parts and liquid charged parts which are subject to leakage, where the gravity system is used.

Accordingly one of the objects of the invention is to provide a simple form of pump and drive therefor designed to be inserted in a low level receptacle and arranged to elevate the liquid therefrom through normally drained conduits to any desired level and which will not require the use of any air tight parts which might affect the actuation of the pump.

Another object of the invention is to provide a construction which will permit of any easy actuation of the parts with the minimum consumption of power and incidental to this object it is a further desideratum to mount the parts, so that the rotating members may be loosely journaled and free of fluid tight connections.

Devices of this class usually require some means for priming the pump and this priming operation requires the consumption of time and results in a material delay before the device can become operative and the engine started.

Another object of this invention is to provide a pump which will be primed at all times and instantly responsive to its inactivating control device.

Another object of the invention is to design the pump so that practically all of the driving mechanism and other parts which

may be affected by conditions within the tank are removed therefrom and positioned so as to be readily accessible for inspection and repairs.

A still further object of the invention is to provide a signaling device operative when the pump has caused a low level liquid condition in the receptacle.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the drawings:

Figure 1 is a view partly in side elevation, of a preferred embodiment of my invention shown installed in a tank and with other parts shown diagrammatically.

Fig. 2 is a view similar to Fig. 1, but showing the device from the left side of the view shown in Fig. 1;

Fig. 3 is a plan view looking down upon the motor parts shown in Fig. 1 with the casing removed; and

Fig. 4 is a horizontal sectional view taken on the line 4-4 of Fig. 2.

In the drawings, there is shown a conventional form of main fuel supply tank, usual in automobile constructions and including an upper wall 10 and bottom 11, the upper wall being provided with a conventional form of inlet opening 12 usually utilized for supplying liquid to the tank.

The device particularly forming the subject-matter of this invention is illustrated as a unitary article of manufacture adapted to be inserted through the inlet opening 12. The article includes a pump element 13 at its lower end adapted to be submerged in the liquid in the tank, and a power system including a motor element 14 positioned exteriorly of the tank and supported on a cover plate 15 which is utilized, not only to support the article in position, but is also utilized to constitute the usual cover for the inlet opening 12.

The pump element is of any conventional rotary type including a hollow barrel casting 16, the lower end of which is covered by a head 17 provided with an intake port 18, 110

opening thereto preferably from a position adjacent the bottom 11 of the tank. The intake port is covered by a screen 19 removably held in position by screws 20, which 5 are also utilized to fasten the head to the barrel. A revolving pump element 21 provided with blades 22 (see Fig. 4) is mounted to revolve within the head 17, as is usual with devices of this character. The pump 10 is provided with a discharge port 23 leading to an upstanding discharge pipe 24. This discharge pipe is in fluid tight connection with the pump barrel and leads upwardly out of the tank through the inlet opening 12 15 and is fixed in the cover plate 15 so as to be removable therewith as a unit. The liquid is discharged from the pipe to any suitable receptacle exteriorly of the receptacle and herein indicated diagrammatically by the 20 pipe 25 which is provided with a pressure gage 26.

The power plant for actuating the pump is mounted within an inclosing casing 27 carried by and preferably constituting a part 25 of the cover plate. Mounted within the casing is a small size, high speed electric motor 28 provided with an armature shaft 29, which depends therefrom, projects through the cover plate and is rigidly attached to 30 the revolving element 21 of the motor to actuate the same. While this shaft is shown to be formed of one length so as to emphasize the rigid driving connection between the electric motor and the pump, it will be 35 understood that the pump shaft may be, and usually is, formed separate from the armature shaft and suitably coupled together, so that there may be a direct drive from the motor to the pump.

40 Current may be supplied to the motor from any suitable source 30 which may be a suitable number of batteries. When the device illustrated is installed as part of an automobile engine construction, it is desirable to include the ignition or magneto in 45 circuit with this motor, so that the closing of the magneto circuit will automatically and simultaneously actuate the fuel-supply pump.

50 On the preferred form of the invention using a one wire system, especially where the device is utilized as part of the driving mechanism of an automobile, it is preferable that one side of the source of electric energy be grounded as by attaching a lead therefrom to the receptacle, the chassis or some other grounding element. Current is supplied from the source 30 to one of the contact posts 31 for the brushes of the motor through a conductor 32, the other brush of the motor being grounded as is usual with devices of this character.

55 It is desirable in such devices to indicate by some suitable signaling device a low level condition of the liquid in the tank and for

this purpose the device illustrated is provided with a signaling device 33, herein indicated diagrammatically by an electric light lamp. The circuit through the lamp is closed by a float controlled circuit closer 34 70 arranged when a low level condition is reached to complete the circuit through the lamp 33 and through conductors which lead from the main supply conductor 32 to a relatively fixed contact rod 35. This contact 75 35 includes a plunger 36 slidably mounted in an insulating sleeve 37 passing through the field-piece 38 of the motor. The plunger is resiliently supported in space by means of a relatively weak coil spring 39 80 so disposed as to support the plunger 36 resiliently and to cushion the engaging movement therewith of a float controlled operating contact plunger 40. The plunger 40 is slidably mounted in a guiding sleeve 41 85 fixed to and depending from the cover plate 15. The plunger 41 is connected by means of a reach rod 42 with the arm 43 of a bell-crank lever organization 44 pivotally supported in position. The other arm 45 of the 90 bell-crank lever is relatively long, so as to reach almost to the bottom of the receptacle and has a float member 46 fixed to the outer end thereof. The float control device is so arranged that when a low level condition of 95 the liquid in the receptacle has been caused by the action of the pump, the float member will be adjacent the bottom of the tank and in a position to cause the plunger 40 and contact rod 35 to make electric contact. This 100 closing of the circuit will cause current to pass from the main supply conductor 32, through a conductor 47 leading to the signaling lamp and therefrom through a conductor 48 leading through a metallic motor 105 part such as the post 31 to the rod 35, and plunger 40. This plunger is grounded on the cover plate 15.

The upper end 49 of the plunger 40 is squared off and may be utilized as an indicator to designate the proportionate amount or level of liquid in the tank. In order to facilitate the reading of this indication a scale 50 is mounted on the supporting plate 15 and in position so that the top of the 110 plunger will move relative to a scale 51 (see Fig. 2) on said plate. The plunger end and coacting scale are visible through a glass covered opening 52 in the lower side of the 115 inclosing casing 27.

120 In order to maintain the motor and pump in fixed relative position a long spacing sleeve 53 is fixed to and extends through the plate 15 and has its lower end fixed to the top of the pump barrel. The armature and pump shafts are journaled loosely in bearing 54 fitted within the sleeve and which acts primarily to steady the action of the long driving shaft. As this sleeve is not intended to act as a fluid conduit it may be made open 130

along the sides and care need be exercised to insure a fluid tight fit between the several parts about this sleeve.

It is desirable under some conditions to provide a means for automatically intercepting current to the motor and to control the same by a liquid level condition either in the receptacle from which the liquid is discharged or by a liquid level condition in a receptacle into which the liquid is discharged.

In the arrangement shown in Fig. 2 the pipe 25 is shown to be discharging into a receptacle 55 which may be regarded as the float chamber of a carburetor. A float 56 is connected to a contact control lever 57 arranged so that normally the weight of the lever and float will cause a closed circuit condition to exist in the circuit closer 58 which is contained in conductor 59 on the grounded side of the source of electric energy.

In operation, and with the tank supplied with a body of the liquid to be elevated which liquid should have a level at least sufficiently high to cause the float controlled device to break contact between the rod 35 and plunger 40, the closing of the circuit through the motor as suggested will cause the same to act promptly and directly upon the pump submerged in the liquid. The pump will act to force the liquid upwardly out of the tank through the discharge pipe and toward the carburetor or other device supplied thereby. There will thus be a constant stream supplied as long as the pump is actuated, and as the intake to the pump is positioned close to the bottom of the receptacle, the pump will continue to supply a stream of liquid practically as long as there is any liquid remaining in the receptacle.

As the liquid level is lowered by the action of the pump, the float 46 will gradually drop until eventually the plunger 40 is moved thereby into contact with the rod 35, thus completing the circuit through the signaling device, causing the lamp to light and thus indicate that a low level condition has been reached within the receptacle. The entire insert may then be lifted out of the receptacle by making the necessary break in the liquid pipe line, but preferably the receptacle is refilled through another inlet (not shown). When the pump is reinserted into operative position in the tank or the tank refilled with the pump in position the higher level of liquid therein will raise the float until the float rod is in the position shown in dotted lines in Fig. 2. In this high level position the plunger 40 will be withdrawn away from the rod 35 thus breaking the circuit through the signaling device.

By means of a device of this character, it is possible to confine the necessity for

fluid tight connections to the pump and discharge pipe, and there is no necessity for maintaining a fluid tight connection through the spacing sleeve, nor is there any necessity for having a fluid tight packing at any place along the pump shaft.

As long as the pump is actuating there will be a fluid pressure within the upstanding discharge pipe, but as soon as the pump stops, any liquid remaining in the pipe promptly drains back into the pump or at least back to the level of the liquid within the receptacle. In this way, there is no liquid left standing in the portion of the supply pipe or other parts exteriorly of the receptacle and accordingly there is no possibility of draining the receptacle due to any leakage in the fluid system.

There is but one pipe line used, this construction assisting to economize in the cost of designing a device of this character. It is obvious that this pipe may be so proportioned so as to coact with an economically actuated type of motor, and the parts of the entire device so arranged that there will be supplied to the carburetor or other receiving body, a constant stream, just sufficient to supply the demands on the device with the least possible consumption of power.

There is no air or gas pressure present in the receptacle, thus avoiding another of the objectionable features in one known type of such devices. As the electric motor is positioned outside of the receptacle, the possibility of firing the contents of a tank by sparking of the motor is reduced to a minimum, if not entirely eliminated. As the motor and in fact practically all of the parts, except the pump and necessary connecting mechanisms is mounted exteriorly of the receptacle ready access is provided for replacing of brushes or other necessary repairs without the necessity of demounting the unit from the receptacle.

When installed as part of an automobile driving plant and in circuit with the magneto circuit, it can start automatically on the closure of the circuit and is in operative position before the starter is used, so that the device may be utilized as a priming device for supplying a priming charge to the carburetor for inaugurating the action of engine.

One advantage of using a pump of the type illustrated is that in case the flow through the pipe 25 is shut off for any reason the pump works idly without causing any material increase of pressure in the pipe and therefore the motor does not have any material extra load to carry with the resulting loss of power and in fact the current consumption is reduced.

Having thus described my invention, I claim:

1. In a device of the class described, the

combination with a tank provided with an opening in the top thereof, a unit demountable bodily from the tank and comprising a cover plate for closing said opening, a pump suspended from said plate and positioned through said opening relatively close to the bottom of the tank, a spacing sleeve fixing the pump to the casing, a motor housing carried by said plate above the tank, a motor positioned in said housing with its armature shaft extending through said sleeve and coupled to the rotary element of the pump in the tank, a discharge pipe connected to the discharge port of the pump positioned to extend parallel to the sleeve, fixed to the plate and extending through said plate and housing.

2. In a device of the class described, a portable unit including a pump adapted to be inserted into a tank to pump liquid therefrom, a motor operatively connected to said pump to actuate the same, means for supporting the motor exteriorly of the tank containing the pump, a discharge pipe leading from the discharge port of the pump and said pump having a capacity to maintain the pumped liquid under pressure in said discharge pipe.

3. In a device of the class described, the combination with a tank provided with a bottom and with a top having an opening therein, of a removable unit comprising a support adapted to close an opening in the top of a tank, a pump depending from said support spaced therefrom a distance to reach almost to the bottom and adapted to pump liquid from the portion of the tank adjacent

the bottom, a motor carried by said support above the tank and operatively connected to the pump to actuate the same, a float constituting a part of the unit inserted in the tank and an indicator above the tank actuated by said float.

4. In a device of the class described, the combination with a tank provided with an opening in the top thereof, of a pump adapted to be inserted into said tank through said opening to pump liquid therefrom and an electric circuit including a motor positioned exteriorly of the tank operatively connected to actuate the pump, an electrically actuated signal positioned exteriorly of the tank, a circuit closer for closing the circuit through the signal to indicate a low liquid level in the tank and a float pivotally mounted within the tank to actuate said circuit closer.

5. In a device of the class described, the combination of a pump adapted to be inserted in a tank to pump liquid therefrom and an electric circuit including a motor operatively connected to actuate the pump, a source of electric energy adapted to be open continuously to the motor, said circuit provided with a normally open shunt circuit including an indicator and a float controlled circuit closer adapted to close the circuit through the indicator when a low level is reached in the tank.

Signed at New York in the county of New York and State of New York this 23rd day of April A. D. 1917.

JULIAN F. DENISON.
